CLUTCH FOR AUTOMOBILES

Rudolf Fuchs, Brunn, Moravia; vested in the
Alien Property Custodian

Application January 17, 1941, Serial No. 374,882
In Bohemia and Moravia February 12, 1940

8 Claims. (Cl. 192—01)

Clutches for use in automobiles are known, which clutches are let in when a certain speed of the motor has been reached.

It is further known to let in motor car clutches automatically, by the aid of damping devices, no shocks being caused thereby.

The present invention relates to a combination of such known devices, in which combination disengagement of the clutch may be effected at any speed desired and even at stand-still of the automobile driving engine.

In the drawing, two embodiments of the invention are shown by way of example. In each of these types, disengagement of the clutch is electrically effected.

Fig. 1 shows diagrammatically one arrangement for electrically controlling the operation of the clutch.

Fig. 2 shows a different form of clutch controlling mechanism using a centrifugal governor.

Fig. 2a is a view of the free-wheel unit used in the form shown in Fig. 2.

Obviously, the means used for controlling the electric current which in the first embodiment (Fig. 1) is a relay, and in the second embodiment (Fig. 2) is a centrifugal governor, may be interchanged in any way desired so that, for example, the first device, instead of by a relay, may be actuated by a centrifugal governor, and vice versa.

In Fig. 1, a bar 1 acting on the clutch C is articulated to a lever 2 which has its fulcrum at 3. At the free end of the lever 2, is mounted a pneumatic shock absorber 6 (known per se) such as, for instance, an automatic and noiseless door closer, acting by the aid of an air damper. Lever 2 is provided with a jawed lug 5 acting as the armature of an electromagnet 4. To such electromagnet, current is supplied from the storage battery B—1 of the automobile. Switching on or off of the current is effected by a coil 7, to which current is fed from the light generator G of the vehicle. One end +D of the coil 7 is connected to the positive pole of the generator, while the other end is grounded or connected to the electric mass of the vehicle, which mass is permanently connected to the negative pole of the generator. When the speed of the engine of the vehicle is low, the output of the generator will be so small that an armature carried by a spring 8 arranged opposite coil 7 and secured to stationary member 9 on the frame of the vehicle cannot be attracted, so that it will be in the position shown in the drawing. Member 9 is electrically insulated from the frame of the vehicle. In this position, the spring 8 is, by its other extremity, applied to a contact 10 connected to the positive pole +B of the storage battery B—1. Thus, the current of the battery will pass through spring 8, member 9, through the winding of the electromagnet 4, and, from there, through the cut-off switch 13 to the electrical mass of the vehicle. Thereby, bar 1, in a direction opposite to the arrow A, is brought into the position shown, in which the armature 5 has been attracted by the magnet. This position corresponds to the disengagement of the clutch C. When the output of the light generator G increases due to an increase of the speed of the engine of the vehicle, the armature of spring 8 is attracted by the coil 7, the contact is interrupted at 10, and the spring 8 abuts stop 11. Thereby, the electromagnet 4 becomes de-energized, the force attracting the armature 5 will cease, and damper 6 retards the movement of bar 1 in the direction of the arrow A, whereby the clutch is softly let into engagement. The customary spring means of the clutch urges bar 1 towards the left of Fig. 1.

In order to enable the clutch to be released when the speed of the engine has not yet sufficiently decreased to bring spring 8 into the position shown, a switch 12 is provided, which is connected to a gas lever L, so that, if the gas supply be completely cut off, the said switch is thrown into circuit. The battery current may now flow through the electromagnet 4, the spring 8 being bypassed. Such operation of the clutch C will take place, for example, when the car starts, for the purpose of changing the speed. When descending, even at the greatest speed of the vehicle, the number of revolutions of the engine will be but small, and therefore, only little fuel will be consumed.

The clutch control mechanism as shown in Figs. 2 and 2a differs from the type as shown in Fig. 1 by that, at the end of a lever 15 having a clutch-operating bar 14 connected thereto, a toothed segment 17 is arranged which meshes with a gear 18, which together with a larger gear 19 is mounted on a gear shaft. The said larger gear 19 meshes with a pinion 20 mounted on the shaft 21—a of an electromotor 21. When this electromotor has been started, lever 15 is moved to the right and into the position shown in the drawing. A stop 22 will prevent the said lever from progressing any further. In this position the clutch is disengaged. Since, as a rule, the device will not remain in this position longer than a few seconds, there is no danger that the motor 21 might be burnt. In case, however, that release of the clutch should take more time, a

special device would be required, which is not described here. Engagement of the clutch is effected if the clutch operating bar 14 is moved in the direction of the arrow A—1, by the strength of springs arranged in the usual manner in the clutch operating device the motor 21 idling in the direction of the arrow A—2. The brake as used in this embodiment is shown in Fig. 2a. On the shaft 21—a of the electromotor 21 is secured a free wheel disc 26 which in the direction of rotation of the arrow A—3 drives a spider 27. This spider is provided with arms 28, on which are pivoted weights 29 fitted to a fixedly arranged brake drum 16. When rotating, the weights, due to the centrifugal force, are pressed against the fixed brake drum 16, and friction is produced, which brakes the rotation. Owing to the free wheeling system 26, such braking only takes place when bar 14 is moved in the direction of the arrow A—1, the motor 21 idling in the direction of the arrow A—2, for engaging the clutch C, while when the clutch is released, the brake is inoperative, and the releasing movement will therefore take place at an undiminished velocity.

Control of the electric current which causes the disengaging movement of the clutch, is, in the clutch control mechanism of Fig. 2, effected in another manner than in the embodiment shown in Fig. 1, namely, not through a relay, but by means of a centrifugal governor 23 driven by the engine of the vehicle. If the speed of the vehicle engine is low, a conducting connection is set up at 25 between the controls of the governor and a contact 24. Thereby, this contact is grounded or conductively connected with the bulk of the vehicle, and also one pole of the electromotor. The other pole is connected, at +B, to the storage battery, so that the motor 21 is started. At a higher speed of the engine of the vehicle the conducting connection is interrupted, at 25, and the clutch is let in. Switch 30 serves the same purpose as switch 12 of Fig. 1.

What I claim is:

1. In an automobile driven by an engine having an accelerator pedal, a driving mechanism comprising a clutch for the engine; electrical means for disengaging said clutch when said means is electrically energized; means for energizing said disengaging means to keep the clutch normally disengaged; means responsive to the operation of the engine for disconnecting said energizing means, to cause said clutch to engage when the engine speed rises above a predetermined point; and means, actuated by the operation of said pedal, for disconnecting said energizing means, to cause said clutch to engage, when the pedal is operated.

2. In an automobile driven by an engine having an accelerator pedal, a driving mechanism comprising a clutch for the engine; electrical means for disengaging said clutch when said means is electrically energized; means for energizing said disengaging means to keep the clutch normally disengaged; means responsive to the operation of the engine for disconnecting said energizing means, to cause said clutch to engage when the engine speed rises above a predetermined point; means actuated by the operation of said pedal for disconnecting said energizing means, to cause said clutch to engage when the pedal is operated; and means for retarding the engaging movement of the clutch when it is released from the said disengaging means.

3. In an automobile driven by an engine having an accelerator pedal, a driving mechanism com-

prising a clutch for the engine; an electrical mechanism for disengaging said clutch; a source of electric current; a first switch; a second switch; an electric circuit connecting the electrical mechanism, the source of current and the two switches, the second switch being shunted across the first switch, and both switches being normally closed to cause the mechanism to disengage the clutch; apparatus responsive to the engine speed for opening the first switch when the speed rises above a predetermined point; and means for connecting the second switch with the accelerator pedal for opening the second switch when the pedal is depressed.

4. In an automobile driven by an engine having an accelerator pedal, a driving mechanism comprising a clutch for the engine; an electrical mechanism for disengaging said clutch, a source of electric current; a first switch; a second switch; an electric circuit connecting the electric mechanism, the source of current and the two switches, the second switch being shunted across the first switch, and both switches being normally closed to cause the mechanism to disengage the clutch; apparatus responsive to the engine speed for opening the first switch when the speed rises above a predetermined point; means for connecting the second switch with the accelerator pedal for opening the second switch when the pedal is depressed; and means for retarding the engaging movement of the clutch when it is released from the action of the electrical mechanism.

5. In an automobile driven by an engine having an accelerator pedal, a driving mechanism comprising a clutch for the engine; an electromagnet for disengaging said clutch; a source of electric current; a first switch; a second switch; an electric circuit connecting the electromagnet, the source of current and the two switches, the second switch being shunted across the first switch, and both switches being normally closed to cause the electromagnet to disengage the clutch; a generator, the electrical output of which depends upon the engine speed; a second electromagnet connected with said generator and adapted to open the first switch when the engine speed rises above a predetermined point; and means for connecting the second switch with the accelerator pedal for opening the second switch when the pedal is depressed.

6. In an automobile driven by an engine having an accelerator pedal, a driving mechanism comprising a clutch for the engine; an electromagnet for disengaging said clutch; a source of electric current; a first switch, a second switch; an electric circuit connecting the electromagnet, the source of current, and the two switches, the second switch being shunted across the first switch, and both switches being normally closed to cause the electromagnet to disengage the clutch; a generator, the electrical output of which depends upon the engine speed; a second electromagnet connected with said generator and adapted to open the first switch when the engine speed rises above a predetermined point; means for connecting the second switch with the accelerator pedal for opening the second switch when the pedal is depressed; and a shock absorber for retarding the engaging movement of the clutch when it is released from the action of the first mentioned electromagnet.

7. In an automobile driven by an engine having an accelerator pedal, a driving mechanism comprising a clutch for the engine; an electric motor for disengaging said clutch; a source of

electric current; a first switch; a second switch; an electric circuit connecting the motor, the source of current and the two switches, the second switch being shunted across the first switch, and both switches being normally closed to cause the motor to disengage the clutch; a centrifugal governor driven by the engine for opening the first switch when the engine speed rises above a predetermined point; and means for connecting the second switch with the accelerator pedal for opening said second switch when the pedal is depressed.

8. In an automobile driven by an engine having an accelerator pedal, a driving mechanism comprising a clutch for the engine; an electric motor for disengaging said clutch; a source of electric

current; a first switch; a second switch; an electric circuit connecting the motor, the source of current and the two switches, the second switch being shunted across the first switch, and both switches being normally closed to cause the motor to disengage the clutch; a centrifugal governor driven by the engine for opening the first switch when the engine speed rises above a predetermined point; means for connecting the second switch with the accelerator pedal for opening said second switch when the pedal is depressed; and a mechanical friction type brake connected with said clutch for retarding the engaging movement of the clutch when it is released from the action of the motor.
